UNITED STATES PATENT OFFICE.

NICK FRANCK BRASACCHIO, OF TAMPA, FLORIDA.

LATHE.

Application filed March 30, 1922. Serial No. 548,113.

To all whom it may concern:

Be it known that I, NICK F. BRASACCHIO, a citizen of the United States, and a resident of Tampa, in the county of Hillsborough and the State of Florida, have invented a new and useful Improvement in Lathes, of which the following is a specification.

This invention relates to lathes especially adapted for use in refacing the valves of internal combustion and other engines.

Briefly stated, an important object is to provide a portable lathe embodying a tubular shaft which receives the stem of the valve and which is rotated at a high speed for presenting the head of the valve to the refacing tool, the said tubular shaft forming a means for properly holding and centering the valve notwithstanding any bends or irregularities which might exist in the valve stem.

A further object is to provide a valve refacing tool having simple means whereby the cutter or file may be quickly and conveniently adjusted to the desired angle.

25 A further object is to provide a lathe of the character specified having simple means whereby to center the head of the valve and to rotate the same at a high speed so that when the refacing tool is gradually fed to the head of the valve an accurate face will be provided, the high speed attained by the head of the valve being possible by the fact that the sleeve which supports the valve is freely rotatable in well lubricated bearings.

35 A further object is to provide a valve refacing tool or lathe which is extremely durable in use, simple to operate and cheap to manufacture.

Other objects and advantages of the invention will be apparent during the course of the following description.

In the accompanying drawing forming a part of this application and in which like numerals are employed to designate like parts throughout the same.

Figure 1 is a perspective of the improved lathe.

Figure 2 is a plan view thereof.

Figure 3 is a group perspective of one of the shaft supporting bearings.

In the drawing wherein for the purpose of illustration is shown a preferred embodiment of the invention, the numeral 5 designates an elongated base having its ends provided with depending frames or legs 6 having attaching lugs 7 secured to a workbench

8 by means of fastening bolts 9. It will be observed that the base 5 is arranged a sufficient distance above the workbench 8 to afford ready recess to the several adjusting devices located beneath the base.

As illustrated in Figure 1, the base 5 is provided with a longitudinally extending slot 10 which receives the squared shanks 11 of a pair of spaced bearing members 12 which rotatably receive a tubular shaft 13. Figure 3 illustrates that the squared shanks 11 are provided with threaded stems 14 having engagement with wing nuts 15 by means of which the bearings 12 may be securely and positively held in an adjusted position.

One end of the tubular shaft 13 is provided with a pulley 16 about which a belt 17 or other power transmitting device is trained. The belt 17 is connected to a suitable source of power and serves to rotate the tubular shaft at a very high speed so that the valve carried thereby will also be rotated at a very high speed.

The stem of the valve is designated by the numeral 19 and is extended into the tubular shaft 13 and may be securely connected thereto by means of a chuck 20. The chuck 20 may be of any desired construction and has its surface roughened so that it may be conveniently turned when it is desired to either loosen or tighten the connection between the shaft and the stem.

The head 22 of the valve is properly centered by means of the centering screw 23 having a hand crank 24 by means of which it may be manually rotated. The forward end of the centering screw 23 is tapered to a point and is extended into the centrally arranged recess in the head of the valve. When the centering screw has been properly positioned it may be locked by means of a jam nut 25 threaded thereon and adapted for abutting the standard 28.

The standard 28 supports the centering screw and is provided with a squared shank extended through the slot 10 and having a threaded stem 30 with which a wing nut 31 is engaged. It will be seen that the standard 28 may be securely held in an adjusted position by means of the wing nut 31. In use, the standard 28 and the bearing members 12 may be adjusted longitudinally of the base for accommodating valves of different lengths.

When adjusting the centering screw 23 it is advanced until the annular shoulder 34 on

the shaft 13 contacts with one of the bearings 12 and the jam nut 25 is then tightened. With the valve thus locked to the shaft 13 it is permitted to rotate with the shaft but is 5 securely held against endwise movement so that when the power is applied an accurate face will be formed on the head of the valve. A refacing tool or cutter 40 is carried by a standard 41 having a set screw 42 which 10 acts to hold the cutter at the desired angle, and in engagement with the face of the head 22. By loosening the set screw 42 the cutter 40 may be adjusted, or if desired the cutter 15 may be quickly removed and a new one substituted.

The standard 41 is formed with a squared shank 45 slidable through a diagonal slot 46 in a lateral projection 47 of the base. The shank 45 is similar in construction to 20 the shank 11 and is securely held in a set position by means of an adjusting nut of any desired type. In the use of the device the nut which holds the standard in position is not tight enough to prevent the feed screw 25 50 from advancing the cutter into engagement with the work. The feed screw 50 is extended out through one side of the machine and is threaded through a standard 60 adjustable diagonally of the base 5. The 30 standard 60 is also provided with a squared shank adjustable in the diagonal slot 46 of the lateral projection 47.

In operation, a valve stem is inserted into the sleeve or tubular shaft 13 and the centering screw 23 is subsequently advanced 35 and locked in position so that the valve is held against endwise movement. The power is now applied to rotate the tubular shaft 13 whereby the head 22 is also rotated. The cutter 40 is now gradually advanced into engagement with the face of the valve so that 40 a new and accurate face is formed. As previously stated any irregularities or slight bends which might be present in the stem 45 of the valve do not in any way interfere with the accurate facing of the valve as the stem

is inserted into the tubular shaft which is supported for rotation by the bearing members 12.

A very high speed is possible because the 50 tubular shaft 13 and the bearings 12 are well lubricated by oil supplied through oil holes 67, none of which is possible without the employment of the tubular shaft.

A lathe constructed in accordance with 55 this invention is extremely simple to operate, durable in use and cheap to manufacture, and further, the refacing operation may be expeditiously performed.

I claim:

1. A valve refacing tool comprising a base having a lateral projection, the base being provided with a longitudinal slot, and the lateral projection being provided with a diagonal slot, a standard having a squared shank, slidable through said longitudinal slot and adjustable therein, a centering screw carried by said standard, a pair of bearings having square shanks adjustable in said longitudinal slot, means carried by said bearings for rotatably supporting a valve, a second standard having a squared shank adjustable in said diagonal slot, a cutter carried by said second standard, a bracket having a squared shank adjustable in said diagonal slot, and a feed screw threaded through said bracket and having engagement with said second standard. 65 70 75

2. A valve tool comprising a base having a longitudinal slot, separate bearings having shanks adjustable in said slot, a valve receiving sleeve rotatable in said bearings and having means to grip a valve stem, a centering screw having a standard provided with a shank adjustable in said slot, said base being provided with a diagonal slot, a cutter having a standard provided with a shank adjustable in said diagonal slot, a bracket having a square shank adjustable in said diagonal slot, and means whereby said shaft 80 85 90 may be rotated.
